UNITED STATES PATENT OFFICE

OSCAR E. MAGNUSON, OF DAVENPORT, IOWA

DOOR LATCH

Application filed May 28, 1930. Serial No. 456,733.

My present invention pertains to that type of devices which are used more particularly in connection with house doors to permit same to be opened a short distance and which can be adjusted to permit the door to open fully and without obstruction or to latch the door in closed position. The present invention is an improvement upon the construction illustrated in my Patent No. 1,754,958 dated April 15, 1930.

Among the objects of this invention are to provide an improved means of the character stated; to provide a device of the character indicated which will be economical to manufacture and efficient in service; to provide a device of the class described which is so constructed that persons outside the door can not actuate the device so as to permit the door to be opened when the latch is in a position to prevent such operation; to provide a device of the character indicated, such that the same may be used to latch the door in closed or partly closed position or may be adjusted to permit the door to be opened; and such further objects, advantages and capabilities as will hereafter appear and as inherent in the construction disclosed herein. My invention further resides in the combination, construction and arrangement of parts illustrated in the accompanying drawings and, while I have shown therein what is now considered the preferred embodiment of my device, together with a modification thereof, I desire this disclosure to be understood as illustrative only and not to be construed in a limiting sense.

In the drawings annexed hereto and forming a part hereof, Fig. 1 is a plan view of one form of this device, showing the same adjusted to a position such that it latches the door in completely closed position; Fig. 2 is a similar plan view showing the parts adjusted to permit the door to be opened slightly; Fig. 3 is a similar view showing the parts adjusted to permit the door to open freely;

Fig. 4 is a view similar to Fig. 1 of a modified form of construction; Fig. 5 is a view similar to Fig. 2 of the device shown in Fig. 4, with a portion of the upper plate broken away to more clearly expose the construction of the latching dog; Fig. 6 is a view similar to Fig. 5 but with the latching dog adjusted to position such that the door may be opened freely, as illustrated in Fig. 3.

The construction will now be described in greater detail in connection with the drawings. In these drawings the door is designated by the numeral 1 and its casing by the numeral 2. A wear-plate 3 is secured adjacent the swinging edge of the door 1 and has two functions, as illustrated in Figs. 1, 2, 4 and 5. In Figs. 1 and 4 it is illustrated as a bumper plate designed to strike against the latching dog 4 when the latter is in latching position, as illustrated in these two figures. With the parts in the position illustrated in these two figures, the plate 3 also has the additional function of tending to prevent the latch 4 from swinging outwardly, if bumped by the door 1, in an attempt to open same. The other purpose of the plate 3 is illustrated in Figs. 2 and 5 in which the hook 5 is shown as engaged by the hook 6 of the dog 4 to assist in holding the parts together when the dog is arranged in the position for permitting partial opening of the door.

The dog 4 is illustrated as being provided with a pivot pin 7 which extends through corresponding slots in the upper and lower plates designated in general by the numerals 10 and 10a. These slots have two arms 8 and 9 arranged at a substantial angle to each other. In order to move the dog 4 from the position shown in Fig. 3 to either of the positions shown in Figs. 1 and 2, it is necessary to turn the same somewhat on its pivot 7 so as to permit the projection 11 to pass the obstruction 12 when the pivot pin 7 slides longitudinally of the slots 8. When this pin has reached the angle between the parts 8

and 9 of these slots, the pin 7 may be moved longitudinally along the portion 9 of the slot and into the end thereof as illustrated in Figs. 1 and 2. When arranged in this way, it is 5 possible to turn the dog 4 into either the position shown in Fig. 1 or that shown in Fig. 2. A pair of notches 13 and 14 are provided for entrance of the projection 12, as illustrated in Figs. 2 and 3. As illustrated in the 10 various figures, the device is provided with suitable flanges 15 whereby it may be secured to the casing by suitable screws.

The device shown in Figs. 4, 5 and 6 is similar to that shown in Figs. 1, 2 and 3 15 but varies in certain minor details. For example, the slot 16 is a straight or substantially straight slot with a slight enlargement at one end, as illustrated at 17. While the notches 13a and 14a are similar to the notches 20 13 and 14, they differ slightly in form. Also, the projection 12a differs slightly from the projection 12 but it still has the same functions as that projection. A cam 18 is provided on that part of the dog through which 25 the pivot pin 7 passes, said cam cooperating with the projection 19 in rendering it necessary to turn the dog 4 upon its pivot when passing from the position shown in Fig. 6 to either of the positions shown in Figs. 4 30 and 5. The parts 12, 12a and 19 are held in assembled relation with respect to the side plates of the latching device by means of screws or rivets 20 or any other suitable securing means.

35 It will of course be understood that the specific description and other disclosure herein may be departed from without departing from the spirit of my invention as expressed in the following claims.

40 Having now described my invention, I 105 claim:

45 1. In a door latch, a body member comprising a pair of flanged side members having a spacing block between them, said side members being slotted for the reception of a pin, a dog arranged between the side members and provided with a pin extending through said slots, said dog being mostly exposed outside of the body member and having a hook for 50 engagement with a door, said dog having a pair of notches to cooperate with the spacing member in permitting such movements of the dog.

55 2. In a structure of the character described, a wear-plate to be attached to a door, a latching member to be attached to a door casing adjacent the door and in a position to contact with the wear-plate in one position of adjustment of the latching member, said latching member comprising a hollow body having a pair of substantially parallel side walls and a dog mounted between said side walls for sliding and pivotal motion between the 60 same, means connecting the dog to the body member for sliding movement therein, said

body member and dog having cooperating parts which necessitate pivotal motion of the dog with relation to the body member when the former slides from unlatching to latching position and vice versa, the cooperating 70 parts comprising a lug on the dog and an abutment on the body member which engage in one position to prevent relative sliding motion of the dog and body member, and in another position to necessitate closing of the 75 door before the dog can be moved.

In testimony whereof I affix my signature.
O. E. MAGNUSON.
